UNITED STATES PATENT OFFICE.

FLOYD O. HUTCHINGS, OF SAN FRANCISCO, CALIFORNIA.

BARBER-POLE.

1,099,879.

Specification of Letters Patent.

Patented June 9, 1914.

Application filed May 23, 1912. Serial No. 699,134.

To all whom it may concern:

Be it known that I, FLOYD O. HUTCHINGS, a citizen of the United States, residing in the city and county of San Francisco and State of California, have invented new and useful Improvements in Barber-Poles, of which the following is a specification.

This invention relates to advertising signs, and particularly to barber poles.

It is the object of the present invention to provide a barber pole, or other advertising sign, involving a movable member which may be decorated with suitable or divers colors, and to combine with such a pole an electric lighting system, the movable member of the sign and the electric system, which may include lights of various colors, being controlled and operated by a common source of power.

The invention consists of vari-colored electric lamps mounted in a translucent or other globe on the pole; the illumination of the lights being controlled by a switch mechanism operable by a motor which is arranged to drive or move the movable element of the sign.

It also comprises details of construction which will be more fully explained by reference to the accompanying drawings, in which—

Figure 1 is a vertical sectional view through the pole. Fig. 2 is an underneath plan view of the switch disk.

In order to render conspicuous and attractive both by day and night signs advertising various business establishments, I have evolved the present invention, which consists in part of a rotary cylinder or its equivalent 2, having suitable decorations, as color bands 3, on its surface; the cylinder 2 in the present instance being supported and suspended by a hanger 4 which projects upwardly through an annular cap or cover 5. The hanger is provided with an adjustable collar 6, running on a ball-bearing 7, mounted on the upper portion of the cap 5.

The cylinder 2 is protected by an exterior, transparent, glass casing or shell 8 which is fitted in the cap 5 and rests upon a base 9; the cap 5 in the base being suitably and rigidly connected by one or more bolts 10 which may be inclosed for decorative purposes in polished or otherwise finished tubes 11 abutting at their ends against the cap 5 and the base or bottom member 9. Resting

upon the upper portion of the cap 5 is a crown or bonnet 12 of ornate design, upon which is superposed a transparent or translucent globe 13 of desired proportions. Within the globe 13 is arranged a cluster 60 of lights 14 to which current is conducted through a lead wire 15 which runs downwardly through the crown 12 and through the cap 5 into one of the spacing tubes 11, 65 and thence outwardly through the base member 9.

The conductor 15 is common to the lamps 14, and to each of the lamps is attached separate conductors 16 which are carried downwardly in the form of a cable 17 through one of the tubes 11; the conductors 16 being connected to respective, several brushes 18 which bear upon a switch disk 19 which is provided with an annular conductor 75 20, Fig. 2, which is energized by a lead wire 21 in circuit with the lead wire 15.

The switch disk 20 is provided with a concentrically arranged series of segmental insulators 22, movable over the lamp wire 80 brushes 18, so that these will be successively energized and the lamps 14 successively or simultaneously illuminated, as the case may be, during the rotary movement of the disk 20, which is shown as being secured to a 85 shaft 23 extending from a suitable spring motor 24 which is secured to the bottom of base member 9.

Power is transmitted from the spring motor 24 through a driving spindle 25, which 90 is quickly and easily coupled to a coupler 26 secured on the lower end of the rotary, decorated drum or cylinder 2. However, the coupler 26 does not bear downwardly upon the spindle 25 of the clock-work with any 95 degree of pressure; the entire load of the cylinder 2 being carried by the ball-bearing 7, since any downward pressure of the coupler 26 upon the spindle 25 would tend to stop the clock-work. The coupling connection between the members 25 and 26 is of that nature designed to transmit a rotary movement to the cylinder 2; the coupling device permitting free, endwise movement either of the cylinder 2 or the driving spindle 25.

In order to effectually protect and cover the mechanism in the lower part of the apparatus, I attach to the lower side base plate 9 a suitable shell or cover 27, which may be 110 fastened by means of the bolts or other devices 10 which unite the sections.

For the purpose of regulating the speed of rotation of the cylinder 2, I have shown as connected to the upwardly projecting portion of the hanger 4 a rod 28, on the 5 upper end of which is pivotally suspended, as at 29, levers 30, carrying weights 31 adapted to be thrown outwardly by centrifugal force when the rod 28 is rotating to carry friction devices or shoes 32 into engagement with a friction plate 33, which is disposed in a plane above the orbit of the 10 shoes 32.

When the cylinder 2 is rotated, the governor balls 31 are thrown outwardly and 15 the friction of the shoes 32 rubbing on the friction plate 33 is sufficient to check the rotary movement of the cylinder under the impulse of its driving motor 24. The friction disk 33 is adjustable, vertically, by 20 means of a set-screw or other equivalent device 34 so that the desired speed of rotation of the cylinder 2 may be readily obtained.

After the clock-work or motor 24 has been wound and permitted to run, it will revolve 25 the cylinder through means of the loose coupler 25-26, and when a certain speed is attained the governors 31 will come into effect and thereafter control the speed of 30 rotation of the cylinder 2; meanwhile the disk switch 19 is being rotated by the spring motor 24 and the circuits of the lamps 14 successively or simultaneously closed when the several brushes 17 rest upon the common 35 conductor 20 of the disk switch 19.

From the foregoing it will be seen that by day the device is rendered attractive, conspicuous and effective, due to the rotation of its decorated or suitably placarded cylinder or drum 2, and at night when the drum 40 would ordinarily become invisible, or nearly so, from a distance, the utility of the sign is conserved and its value increased by means of the illuminated lamps 14, which, as before stated, may be successively or simultaneously 45 lighted.

The device is particularly effective for advertising barbers' establishments, since

the lamps 14 may be variously colored, and when successively lighted each of the different colors, usually red, white and blue, will 50 be radiated from the globe 13. At certain intervals the switch 19 will rotate to close the circuit in all of the lamps 14 at one time, thereby giving a very unique and attractive effect. 55

The device may be attached to any appropriate or convenient support by any desired means. A simple form of attachment is illustrated in the present instance as including brackets or hangers 35 which may be 60 screwed or bolted, as at 36, to the top and bottom members 5 and 9 and the brackets screwed or fastened to the contiguous support by screws 37.

Having thus described my invention, 65 what I claim and desire to secure by Letters Patent is—

In an advertising sign in combination, a cylindrical sign member mounted to rotate on a vertical axis, a motor for driving said cylindrical sign member and located beneath the same, a non-transparent casing surrounding said motor, a cylindrical glass casing surrounding said cylindrical sign member, a non-transparent crown above said 70 glass casing, a loose connection between the lower end of said cylindrical sign member and said motor, a governor on the upper end of said cylindrical sign member to always maintain the said loose connection 75 under tension from the motor, said governor being located within said non-transparent crown, a transparent stationary globe above said crown, stationary lights within said globe, and means operated by said motor for 80 intermittently controlling said lights. 75

In testimony whereof I have hereunto set my hand in the presence of two subscribing witnesses.

FLOYD O. HUTCHINGS.
